EARTH MOVING MACHINE

Louis A. Grant, 501 Virginia Ave., Oakmont, Pa.

Filed Oct. 17, 1958, Ser. No. 767,942

3 Claims. (Cl. 262—13)

This invention relates generally to earth moving machinery and more particularly relates to a drill accessory or attachment for such machinery to enable remotely controlled drilling over a wide angle of tilt relative to the boom, thereby enabling drilling in heretofore inaccessible places.

An outstanding disadvantage in the use of pneumatically operated drills or air hammers has been that the operators handling such drills had to be exposed to the danger of dust and flying particles of stone as well as excessive vibration of the drill.

An object of the present invention is to provide pivotally movable attachment whereby a pneumatically operated drill or air hammer can be remotely controlled as a component part of an earth moving machine, such as one sold under the trademark "Gradall."

A further object of the invention is to provide an accessory for an earth moving machine, which accessory enables turning of a pneumatically operated drill through a wide angular range so as to make the drill useful for a wide variety of applications, such as for digging brick linings, and those of oxygen furnaces and open hearth furnaces, and similar applications.

Other objects or advantages of the invention will become more apparent from a study of the following description taken with the accompanying drawings wherein:

Fig. 1 is a top, plan view showing a drill mounting or accessory attached to a boom, shown cut away, and illustrating the principles of the present invention.

Fig. 2 is a side, elevational view of the assembly shown in Fig. 1, the dot and dash outline showing the lowermost angular position of tilt of the drill.

Fig. 3 is a side elevational view of a modification including a drill and bucket.

Fig. 4 is a cross-sectional view taken along line 4—4 of Fig. 3; and

Fig. 5 is a side elevational view of a further modification showing a boom mount which is rotatable about its own axis through an angle of 360°.

Referring more particularly to Figs. 1 and 2 of the drawing, numeral 2 denotes a fragmentary portion of a boom of an earth moving machine, such as sold under the trademark "Gradall" and which is illustrated in Fig. 5. Numerals 3 and 4 denote clamps for rotatably mounting a sleeve 5 which is rigidly secured to a cradle 6. Mounted in the cradle 6 is an air hammer or pneumatically operated drill 7 which is clamped onto the cradle by means of stationary clamps 8 and 9. The air hammer 7 is supplied by air under pressure through flexible tubing 10 connected to a coupling 11 which, in turn, is connected to an air pump or other suitable source of air pressure mounted on the vehicle. The air hammer 7 has attached thereto a bit or drill 7a which is reciprocated along the axis of the hammer 7 in a well-known manner.

It will appear that the cradle 6 is pivotally movable through a wide range of angles relative to boom, extending from the position shown in full lines in Fig. 2 to that shown in dotted lines as indicated by numeral 17. The

2

linkage for effecting such angular movement of the drill comprises a link 15 having an end portion pivoted at 16 to the cradle 6 and another end portion connected to a rocker arm 18 pivoted on shaft 12. Thus an effective parallelogram linkage is provided. Thus, the crane operator, by well known control means at the cab, after the boom is suitably extended may tilt the rocker arm 18 to any desired angular position about shaft 12 as a center, so as to secure any desired angle of tilt of tool 7a with respect to the boom, through a range of a horizontal position, as shown, to a vertically downwardly position as illustrated in dash and dot lines.

Figs. 3 and 4 show a modification which is similar to Figs. 1 and 2 except that a bucket 19 of conventional type is mounted, at its forward and rearward end portions, to cradle 6 so as to enable the operator to selectively use either the drill or the shovel 19 depending on the operation desired. At the rearward portion, clamps 20 and 20a are rigidly secured to the shovel and to sleeve 5. In some instances, both operations may be used alternately, that is to say, the drill may be used for loosening up rock on the forward motion and then upon rearward motion, the shovel 19 may be used to scoop up the broken rock.

Fig. 5 shows a further modification of the invention which enables the Gradall operator to move the cradle 28 and drill 30 to any desired angle of tilt, even in a vertically upward direction. More specifically, the Gradall or other earth moving cab 21 has control means by which the boom 24 is pivoted on brackets 22 and 23 so as to move through a vertical plane. In addition, means are provided, which include gear 27 driven by a pinion (not shown) whereby the entire boom 24 may be rotated through an angle of 360° about its own longitudinal axis. The boom extension 25, of course, may be telescoped with respect to boom portion 24 so as to extend the length of the boom. Thus, not only is the cradle 28 movable about the pivot 29 through an angle of substantially 90°, since it is of the same construction as shown in Figs. 1 and 2, but the entire boom, upon rotation about its own axis, will enable the drill 30 to be moved also throughout a 360° arc in a vertical plane at right angles to the boom and thereby enable movement of the tool throughout a hemispherical path of movement. This is particularly desirable in instances where it is desirable to drill into the roof of a structure or into a portion which is above the boom.

Thus it will be seen that I have provided an efficient accessory for an earth moving machine, such as one known by the trademark as Gradall, which accessory is readily attachable to the forward end portion of a boom so it may serve as a mounting for a drill or other tool and which will enable the tool to be angularly vertically moved from the horizontal position; furthermore, I have provided a further improvement whereby the aforesaid tool may be additionally moved throughout a circle of 360° in a vertical plane at right angles to the boom to allow a wide variety of angular movement of the drill or other tool with respect to the boom and thus enable digging into roofs and into practically any inaccessible place.

While I have illustrated and described several specific embodiments of my invention, it will be understood that these are by way of illustration only, and that various changes and modifications may be made within the contemplation of my invention and within the scope of the following claims.

I claim:

1. An earth moving machine including a boom, a cradle having an end portion pivotally connected to the free end of said boom, linkage means connecting a free end portion of said boom to a portion of said cradle laterally offset

from said pivotally connected, cradle end portion for pivotally moving said cradle through an angle of substantially 90° with respect to the longitudinal axis of said boom, a pneumatically operated tool seated within said cradle, clamp means extending transversely across the top of said cradle for clamping said tool therein, said cradle and tool being so proportioned with respect to the free end portion of said boom so as to be substantially wholly contained within the space defined by longitudinally projecting the free end portion of said boom when the cradle and boom are in a position wherein their longitudinal axes are substantially coextensive with the longitudinal axis of said boom, whereby the drill, cradle and boom may be projected through relatively small openings, and whereby the drill may be selectively moved from a position substantially coextensive with the longitudinal axis of said boom to one substantially at right angles thereto.

2. An earth moving machine as recited in claim 1 together with a bucket suspended by a said cradle to enable selective operation of said tool or said bucket.

3. An earth moving machine including a boom mounted on said machine having telescoping parts and being rotatable about its longitudinal axis throughout an angle of substantially 360°, a cradle having an end portion pivotally connected to the end portion of the outermost part of said boom, linkage means connecting said last mentioned end portion to a portion of said cradle laterally

- 5 offset from said pivotally connected, cradle end portion for pivotally moving said cradle through an angle of substantially 90° with respect to the longitudinal axis of said boom, a pneumatically operated, tool seated within
 10 said cradle, clamps extending transversely across the top of said cradle for clamping said tool therein, said cradle and tool being so proportioned with respect to said outermost part of the boom so as to be substantially wholly contained within the space defined by longitudinally projecting said outermost part when the cradle and boom are in a position wherein their longitudinal axes are substantially coextensive with the longitudinal axis of said boom, whereby the drill, cradle and boom may be projected through relatively small openings, and whereby the drill
 15 may be selectively moved throughout substantially a hemispherical path to enable digging into ceilings, walls and floors at selective angles.
